US00D587013S

(12) **United States Design Patent**
Hand

(10) **Patent No.:** **US D587,013 S**
(45) **Date of Patent:** **** Feb. 24, 2009**

(54) **TOOL CHEST**

(75) Inventor: **Jim Hand**, Glen Ellyn, IL (US)

(73) Assignee: **Waterloo Industries, Inc.**, Oak Creek, WI (US)

(**) Term: **14 Years**

(21) Appl. No.: **29/305,829**

(22) Filed: **Mar. 28, 2008**

(51) **LOC (9) Cl.** **03-01**

(52) **U.S. Cl.** **D3/318; D3/905; D6/510**

(58) **Field of Classification Search** **D3/260, D3/272-273, 276, 283, 297, 312-322, 905; D6/396-397, 432, 437-441, 445, 491, 509-510; 312/308, 351, 902; 206/349, 372-373, 376-379**
See application file for complete search history.

(57) **CLAIM**

I claim the ornamental design for a tool chest, as shown and described.

DESCRIPTION

FIG. 1 is a perspective view of a tool chest of the new design; FIG. 2 is a front elevation view of the tool chest of FIG. 1; FIG. 3 is a rear view of the tool chest of FIG. 1; FIG. 4 is a left side view of the tool chest of FIG. 1; FIG. 5 is a right side view of the tool chest of FIG. 1; FIG. 6 is a top view of the tool chest of FIG. 1; and, FIG. 7 is a bottom view of the tool chest of FIG. 1.

The phantom lines in the drawings are illustrative of environment and form no part of the claimed design.

1 Claim, 6 Drawing Sheets
